UNITED STATES PATENT OFFICE

168,075

LADY'S SUSPENDER BELT

Henry H. Thorne, Chicago, Ill.

Application March 13, 1951, Serial No. 14,473

Term of patent 14 years

(Cl. D3—10)

To all whom it may concern:

Be it known that I, Henry H. Thorne, a citizen of the United States, residing in Chicago, county of Cook, State of Illinois, have invented a new, original, and ornamental Design for a Lady's Suspender Belt, of which the following is a specification, reference being had to the accompanying drawing, constituting a part hereof.

Figure 1 is a front perspective view of a lady's suspender belt, showing my new design and it appears in unfastened position with one of the suspender straps partially detached.

This application is a continuation-in-part of my earlier-filed application, Serial No. D. 8,365, filed March 6, 1950, and now abandoned.

I claim:

The ornamental design for a lady's suspender belt, substantially as shown.

HENRY H. THORNE.
